HYDRAULIC POWER APPARATUS

Lewis Ferry Moody, Princeton, N. J.

Application November 22, 1933, Serial No. 699,230

18 Claims. (Cl. 253—117)

This invention relates to hydraulic turbines of the reaction type. It is applicable particularly to such turbines provided with draft tubes of the elbow type, but may also be advantageous 5 in turbines having certain forms of symmetrical draft tubes.

One object of the invention is to eliminate or to minimize the loss of energy and efficiency caused by the formation of a void within the 10 flowing stream below or downstream from the central hub of the runner and to avoid the still more serious consequences of the "cavitation" action due to such a void, including vibration, water hammer, instability of operation, pitting 15 or corrosion, and loss of power capacity.

The invention is particularly advantageous when applied to propeller type turbines, owing to the relatively high velocities of flow in the draft tube below the runner of such turbines, 20 and especially when used in adjustable-blade propeller turbines, in which the runner hub is made relatively large in diameter as required by the mechanical design necessary for the blade adjustment. In propeller turbines of the adjustable blade type as commonly designed, the 25 large hub produces a correspondingly large void within the flowing stream, with an increased tendency toward cavitation and consequently a restricted range of heads and draft heads which 30 may be employed.

Other objects and advantages of the invention will be apparent from the following description and claims.

In general the means introduced herein for 35 eliminating the cavity formation comprises, first, a generally cylindrical structure forming part of the stationary draft tube and forming in its contour a continuation of the contour of the runner hub; and second, a vertical pier (in vertical shaft turbines) extending from this cylinder in a downstream direction toward the final discharge into the tailrace. The cylinder fills the central region below the runner and prevents the formation of a void or cavity within the flow 40 lines of the stream, and thus eliminates a space filled with eddying water, air or vapor or a mixture of these, and the action which occurs in such a space when the pressure approaches the barometric limit, namely, the collapsing or explosion of the vapor filled cavity and resulting 45 water hammer, vibration and instability of flow. The tendency toward the formation of a cavity in the central region of the draft tube is accentuated in turbines of high specific speed, including both propeller and high-speed Francis tur-

bines, due to the whirl components of the discharge velocity from the runner. When a whirling element of the flow approaches the axis, the moment of momentum of the rotating mass tends to increase the velocity of whirl in inverse proportion to the radius, and increase in velocity head causes a corresponding reduction of pressure head until the barometric limit is reached. The same conditions occur in turbines of lower specific speed when running at part 10 load or overload. The longitudinally extending pier forms a continuation of the cylindrical surface on one side, thus cutting away a portion of the cylinder wall and replacing it with a solid, stationary body, to prevent the formation of a 15 void or cavity in the flow due to those components of the flow velocity which are directed transversely of the cylinder and would otherwise produce a cavity on the downstream side of the cylinder. The pier also provides a firm structural support for the cylinder and contributes to the support of the superposed structure of turbine unit and powerhouse.

The invention is illustrated by a number of embodiments shown in the following drawings: 25

Fig. 1 is a sectional elevation of an adjustable blade propeller turbine and adjacent parts of powerhouse on line 1—1 of Fig. 2;

Fig. 2 is a horizontal section of the draft tube of Fig. 1 on line 2—2 of Fig. 1;

Fig. 3 is a sectional elevation of a fixed-blade propeller turbine, the draft tube being identical with that of Fig. 1 except for a reduction in diameter of runner hub;

Fig. 4 is a vertical transverse section of the 35 turbine of Fig. 3 on line 4—4 of Fig. 3 looking upstream. Except for the change in diameter of hub and cylinder, this view also represents a corresponding section of the draft tube of Fig. 1;

Figs. 5 and 6 are corresponding longitudinal 40 and transverse vertical sections of a modified tube; and

Fig. 7 is the corresponding horizontal section on line 7—7 of Fig. 5. In this modification the longitudinal pier is reduced in thickness below 45 the diameter of the hub;

Fig. 8 is a horizontal section of draft tube similar in longitudinal section to Figs. 1 and 3 but having a curvature where it joins the cylindrical portion as shown in Fig. 8;

Fig. 9 is a longitudinal section of a draft tube similar to those of Figs. 1 to 3 but with the central pier extended on the upstream side of the cylinder to the upstream wall of the tube;

Fig. 10 is a transverse section of the tube of Fig. 9 on line 10—10 of Fig. 9 looking downstream;

Fig. 11 shows in longitudinal section a modification of Figs. 1 to 4, showing the addition of a 5 deflecting guide plate or baffle;

Fig. 11a shows the application of my invention to a Francis runner;

Fig. 12 is another modification in which the 10 central cylinder is supported laterally by diffusion vanes below the runner, the longitudinal pier extending from the cylinder being omitted;

Fig. 13 is a further modification in which the 15 lower part of the cylinder is omitted and a short stationary cylinder and cone element below the runner hub is supported by diffusion vanes;

Fig. 14 is a still further modification in which 20 the lower part of the cylinder is supported by a longitudinal pier and the upper part by diffusion vanes. The figure also shows a guiding plate or baffle which can be added when desirable.

In Fig. 1 the water enters the turbine through 25 the casing 1, here of volute form, passing through the stay vanes 2, wicket gates 3, transition space 4, and runner 5. The blades of the runner are 30 rotatably adjustable in the hub 6, being actuated by the servo-motor 7 mounted in the shaft. The water passes from the runner into an elbow draft tube 8 which has a gradually directed horizontal discharge portion 8a discharging into the tail race 35 9. Below the runner is a central core 11, here shown as of cylindrical shape, registering with the runner hub in contour. Suitable clearance is provided between the stationary core and the revolving hub. The core or cylinder will usually 40 be constructed of reinforced concrete, and the upper part may be provided with a cast or plate metal covering as shown in Moody Patent No. 1,683,567 and Taylor Patent No. 1,681,712. Within the horizontal discharge portion of the draft 45 tube is a vertical longitudinal pier 12 which is continued upstream into the elbow portion of the tube, joining and merging with the central core or cylinder 11 which forms an upstream nose or rounded entrance edge for the pier.

The same general form of draft tube is shown 50 in Figs. 2 to 4, slightly modified to suit the smaller hub of a fixed blade propeller runner. The same symbols have been repeated in these figures. The upper edge of the longitudinal pier where the 55 water first meets it is curved as shown at 13 in Fig. 4 to suit the oblique direction of flow due to the whirl components of the discharge velocity from the runner. It will be understood that the same general formation may be used with Francis runners R as shown in Fig. 11a, and the various draft tube features shown in all the figures are not limited to one particular form of runner.

The longitudinal pier in the elbow portion of 60 the draft tube serves three purposes. It provides a continuation of the central core or cylinder in the downstream direction so that the flow passing around the outer portion of the elbow and flowing laterally past the lower part of the 65 cylinder on its way toward the tailrace will not form a void or cavity within the stream on the downstream side of the cylinder. The pier also provides a strong lateral support for the cylinder which is a structural requirement and furnishes valuable support for the superposed portion of the powerhouse. The pier with its properly curved upward portion serves another hydraulic function namely that of a guide blade to control the whirl components and gradually to 70 reduce their amount, thus straightening and 75

smoothing out the flow while it passes around the elbow and eliminating counter flows and interferences.

In some cases, particularly with adjustable-blade runners having large hubs as required by 5 the blade adjusting mechanism within them, it may not be desirable, structurally or hydraulically, to maintain the cylindrical core in the draft tube at the full diameter of the hub. Figs. 5 and 6 show a formation in which the core is gradually tapered downward to a smaller diameter. It may also in some cases be desired to reduce the thickness or the longitudinal pier, when a greater thickness is not needed for strength, below that of the cylinder. This modification is shown in Fig. 15 10 7 which is a horizontal section corresponding to Figs. 5 and 6. Here the cylindrical core forms a nose or rounded entrance edge for the pier and is curved on a gradual taper into the contour 20 of the thinner pier.

When desired, the discharge portion of the draft tube may be offset from the axis of the turbine to suit the whirl components of the flow entering the tube. When this is done, the longitudinal pier may be offset and curved into the 25 cylinder as shown in Fig. 8.

To accentuate the guiding function of the longitudinal pier and to provide additional lateral support for the cylinder, it is in many cases desirable to continue the pier to the upstream wall 30 of the draft tube, as shown in Figs. 9 and 10. Here, as indicated by the solid and dotted lines 14 and 15 in Fig. 10, the entrance edges of the pier must be curved in opposite directions to conform to the angle of the whirling flow.

In Fig. 11 is shown a further modification, the addition of a transverse guide plate or baffle 16. This is to guide the flow while passing around the elbow and to avoid cross currents and distorted 40 velocity distribution and to discharge the water smoothly and with nearly uniform velocity into the horizontal discharge section of the tube. It permits more rapid and efficient deceleration of the curving flow. It also furnishes additional structural support for the cylinder and pier in a 45 lateral direction. In Fig. 11 the baffle is shown as a steel plate (either plate steel or casting) inserted into the concrete pier and cylinder. If desired, it may be made thicker and formed of 50 reinforced concrete.

It extends horizontally on both sides of the pier, its ends being imbedded in the concrete side walls of the draft tube. Instead of placing the curved guide plate or baffle on or near the centerline of the passage, it is preferable, as shown in Fig. 11, 55 for hydraulic reasons to place it slightly higher and slightly downstream from the centerline of the passage so that it will more efficiently guide the more rapid flow which occurs along the inside surface of the bend and upper surface of the passage. This may be understood when it is considered that the velocity of flow tends to increase toward the inner surface of the bend because the centrifugal forces of the curving stream elements increase the pressure head at the outer wall of 60 the bend and reduce it at the inner wall, and the velocity head increases by the amount that the pressure head is reduced. Consequently the velocities are highest near the inner wall of the bend, greater quantities of flow will pass through 65 the innermost half of the passage than through the outermost half, and the central flow line will be displaced inwardly from the curved centerline of the passage. Furthermore, since the innermost portion of the stream is flowing at higher 70 75

velocities while at the same time curving, in most 5
elbows, along lines of sharper curvature or smaller
radii of curvature, this portion of the stream more
strongly demands guidance than the outer por-
tion. In addition to these considerations, there
is a strong tendency for the flow to depart from
the inner surface of the bend, leaving regions of
backward flow and turbulence. For these reasons
it is advantageous to locate the curved baffle not
10 along the centerline of the passage but nearer the
inner surface of the bend and farther from the
outer surface, thus dividing the cross-sectional
area of the passage into two unequal portions, the
innermost portion being the smaller. As a gen-
15 eral guide to a suitable amount of displacement
of the baffle from the center of the passage, an
approximate rule, subject to some degree of modi-
fication depending on the particular design of
elbow, is as follows: (see Fig. 11). In a given sec-
20 tion ON of the passage transverse to the center-
line CL, if the center of curvature O of the center-
line is located and the distances from this center
of curvature to the inner surface of the elbow,
25 to the center of the baffle, and to the outer sur-
face of the elbow are denoted respectively by a, b
and c, then the baffle should be so located in the
section ON that b is equal to or slightly less than
a mean proportional to a and c; that is

$$\frac{a}{b} = \frac{b}{c}$$

or

$$b = \sqrt{ac}$$

30 By the use of such a baffle in addition to the cen-
tral pier here shown, very efficient guidance and
deceleration of the discharge can be effected. It
will be noted in Figs. 11 and 14 that the partition
is generated by straight lines perpendicular to the
40 center line of the elbow and in the central section
of the elbow the partition at its inflow end lies
substantially in the center line of the passage but
that in proceeding downstream the partition
45 deviates from the center line by increasing
amounts until the discharge end is reached, this
deviation from the center line being in a direc-
tion toward the center of curvature of the walls
of the elbow.

Fig. 12 shows a generally cylindrical central
core 17, laterally supported by cast metal guide
50 and stay vanes 18 near its upper end. These
vanes are spaced from the runner to provide a
free transition space 19, and are curved slightly
to conform to, and to produce, a gradual reduc-
55 tion of whirl components of velocity and obliquity
of flow.

Fig. 13 shows a further modification in which
the lower part of the central cylindrical core is
omitted and replaced by a curved tapering nose-
piece 21, supported by guide and stay vanes from
0 the wall of the draft tube. It will be understood
that for simplicity the draft tubes in the various
figures have been shown as if constructed entirely
of concrete. Actually in most cases metal liners
will be provided in the upper portions near the
runner, such as shown in Moody Patent No.
1,583,415. When stay vanes such as in Figs. 12
and 13 are used, these can be made integral with,
or attached to, such metal liners at the wall of the
tube.

Fig. 14 shows a combination of the guide vane
construction of Fig. 12 with a guide plate or baffle
20 similar to 16, Fig. 11. Here both upper and
lower portions of the central cylindrical core are
directly supported in all directions. It may be
noted that when guide vanes of the type shown

in Figs. 12 to 14 are used with adjustable-blade
runners, somewhat less curvature and inclination
are usually needed for the guide vanes, since the
whirl components are somewhat reduced.

By the use of the various features of the inven- 5
tion described herein the formation of voids or
cavities within the flowing stream is prevented,
more positive guidance is provided for the flow,
and unforeseen departures from smooth lines of
flow are prevented together with resulting turbu- 10
lence, irregular turbine operation, cavitation and
accompanying disorders. Further modifications
in accord with the principles of the invention will
occur to those skilled in the art in applying it to
particular conditions. 15

I claim:

1. In a vertical shaft hydraulic turbine having
a runner, an elbow draft tube having a discharge
passage for discharging the flow downstream into
the tailrace, said draft tube including a stationary 20
central core of diameter substantially the same
as that of the runner hub and formed as a con-
tinuation thereof, said core extending coaxially of
said runner on the discharge side thereof, and a
vertical central pier extending laterally from said 25
core into the discharge passage in a downstream
direction toward the tailrace and extending verti-
cally from top to bottom of the discharge passage
and having side surfaces merging into the surface
of said core. 30

2. In a vertical shaft hydraulic turbine having
a runner, an elbow draft tube having a discharge
passage for discharging the flow downstream into
the tailrace, said draft tube including a stationary
central core of diameter substantially the same as 35
that of the runner hub and formed as a continu-
ation thereof, said core extending coaxially of
said runner on the discharge side thereof to the
bottom surface of the draft tube, and a vertical
central pier extending laterally from said core 40
into the discharge passage in a downstream di-
rection toward the tailrace and extending ver-
tically from the bottom surface of the draft tube
to a point above the top surface of the discharge
passage and having side surfaces merging into the 45
surface of said core.

3. In a hydraulic turbine having a runner, an
elbow draft tube having a discharge passage for
discharging the flow substantially at right angles
to the runner axis, said draft tube including a 50
stationary central core of diameter substantially
the same as that of the runner hub and formed
as a continuation thereof, said core extending co-
axially of said runner on the discharge side there-
of, a vertical central partition extending laterally 55
from said core in the central plane of the dis-
charge passage and having side surfaces merg-
ing into the surface of said core, and a transverse
partition curving longitudinally and disposed
nearer to the inside bend of the elbow tube 60
than to the outside thereof substantially through-
out its length.

4. In a vertical shaft hydraulic turbine having
a runner, an elbow draft tube having a discharge
passage for discharging the flow downstream in- 65
to the tailrace, said draft tube including a verti-
cal central pier extending downstream into said
discharge passage and upstream as far as the run-
ner axis and terminating at its upstream end in
an upper lateral edge having a rounded nose, and 70
having a horizontal thickness substantially the
same as that of the diameter of the runner hub
so as to form a continuation thereof; said pier
extending upward from the bottom surface of the
draft tube and terminating at a point below the 75

runner to provide an unobstructed transition space between the runner and upper edge of said pier.

5. In a vertical shaft hydraulic turbine having a runner, a draft tube and discharge passage therefor discharging the flow downstream into the tailrace, said draft tube including a vertical central pier extending downstream into said discharge passage and upstream as far as the runner axis and terminating at its upstream end in a rounded nose, and having a horizontal thickness substantially equal to that of the diameter of the runner hub so as to form a continuation thereof; said pier extending upward from the bottom surface of the draft tube and terminating in an upper substantially horizontal edge at a point below the runner to provide an unobstructed transition space between the runner and upper edge of said pier, said upper edge being rounded and tapered to receive the flow without disturbance.

6. In a vertical shaft hydraulic turbine having a runner, a draft tube and discharge passage therefor discharging the flow downstream into the tailrace, said draft tube including a vertical central pier extending downstream into said discharge passage and upstream as far as the runner axis and terminating at its upstream end in a rounded nose, and having a horizontal thickness substantially the same as that of the diameter of the runner hub so as to form a continuation thereof; said pier extending upward from the bottom surface of the draft tube and terminating in an upper substantially horizontal edge at a point below the runner to provide an unobstructed transition space between the runner and upper edge of said pier, said upper edge being rounded and tapered to receive the flow without disturbance and said pier in its portion immediately below the runner hub being formed as a surface of revolution continuous in contour with the surface of the hub.

7. In a vertical shaft hydraulic turbine having a runner, a draft tube and discharge passage therefor discharging the flow downstream into the tailrace, said draft tube including a vertical central pier extending downstream to the end of said discharge passage and upstream as far as the runner axis and terminating at its upstream end in a rounded nose, and having a horizontal thickness not greater than the diameter of the runner hub; said pier extending upward from the bottom surface of the draft tube and terminating in an upper substantially lateral edge at a point below the runner to provide an unobstructed transition space between the runner and said upper edge of said pier, said upper edge being rounded and tapered to receive the flow without disturbance.

8. In a hydraulic turbine having a runner, a draft tube of generally elbow formation turning the flow and discharging it substantially perpendicularly to the runner axis, said draft tube including a central pier lying in the central plane of the elbow and extending from the outer end of the discharge passage upstream at least as far as the runner axis and also extending from the bottom to the top of the discharge passage, and having in the portion near the axis a thickness substantially equal to that of the runner hub diameter to form a continuation thereof.

9. In a vertical shaft hydraulic turbine having a runner, a draft tube and discharge passage therefor discharging the flow downstream into the tailrace, said draft tube including a vertical central pier extending downstream into said dis-

charge passage and upstream as far as the runner axis and terminating at its upstream end in a rounded nose, and having a horizontal thickness not greater than the diameter of the runner hub; said pier extending upward from the bottom surface of the draft tube and terminating in an upper lateral edge at a point below the runner to provide an unobstructed transition space between the runner and said upper edge of said pier, said upper edge being tapered and rounded with greater taper on one side than on the other to conform to a flow having a whirl component in the direction of runner rotation.

10. In a vertical shaft hydraulic turbine having an adjustable-blade propeller type runner, an elbow draft tube and discharge passage therefor discharging the flow downstream into the tailrace, said draft tube including a vertical central pier extending downstream into said discharge passage and upstream as far as the runner axis and terminating at its upstream end in a rounded nose, and having a horizontal thickness substantially equal to that of the diameter of the runner hub to form a continuation thereof; said pier extending upward from the bottom to the top surfaces of the draft tube and terminating in a lateral edge at a point below the runner to provide an unobstructed transition space between the runner and upper edge of said pier.

11. In a vertical shaft hydraulic turbine having a runner, an elbow draft tube and discharge passage therefor discharging the flow downstream into the tailrace, said draft tube including a vertical central pier extending downstream into said discharge passage and upstream to the upstream wall of the draft tube, and having a horizontal thickness not greater than the diameter of the runner hub; said pier extending upward from the bottom to the top surfaces of the draft tube and terminating in a lateral edge at a point below the runner to provide an unobstructed transition space between the runner and upper edge of said pier, and said pier in its portion immediately below the runner hub being formed as a surface of revolution continuous in contour with the surface of the hub.

12. In a hydraulic turbine or pump having a propeller type runner, a draft tube or diffuser and discharge passage therefor discharging the flow substantially perpendicularly to the runner axis, said draft tube or diffuser containing a central partition lying in the central plane of the discharge passage and extending from the bottom to the top surfaces thereof and also extending upstream at least as far as the runner axis, said partition having a thickness substantially equal to that of the runner hub diameter so as to form a continuation thereof.

13. In a vertical shaft hydraulic turbine having a runner, an elbow draft tube having a discharge passage for discharging the flow downstream into the tailrace, said draft tube including a stationary central core of diameter not exceeding that of the runner hub, said core extending from and coaxially of said runner on the discharge side thereof, and a vertical central pier extending laterally from said core into the discharge passage in a downstream direction toward the tailrace and having side surfaces merging into the surface of said core, and a transverse partition curving from substantially vertical to horizontal in the discharge passage and nearer to the inside band of the draft tube elbow than to the outside thereof substantially throughout its length.

14. In a rotary hydraulic machine having a runner, a velocity decelerating passage of generally elbow formation turning the flow after discharge from the runner and discharging the flow substantially perpendicular to the runner axis, said decelerating passage including a central pier lying in the central plane of the elbow, and a partition perpendicular to said pier curving from a direction substantially parallel to the runner axis at its entrance end to a substantially perpendicular direction at its discharge end and located substantially throughout its length nearer to the inside and downstream surface of the elbow than to the outer and upstream surface, said partition being so located in a section transverse to the centerline of the passage that its distance from the center of curvature of the centerline is not greater than the mean proportional of the distances of said center of curvature from the inner and outer surfaces of the passage.
15. In a hydraulic turbine having a runner, a draft tube of generally elbow formation turning the flow and discharging it substantially perpendicular to the runner axis, said draft tube including a central pier lying in the central plane of the elbow extending from the discharge end of the draft tube upstream at least as far as the runner axis, and having in the portion near the axis a thickness not greater than the runner hub diameter, and a single substantially central horizontal partition curving from substantially vertical to substantially horizontal and having its downstream portion, substantially throughout its length, offset from the centerline of the draft tube toward the upper and inner surface of the elbow.
16. In a hydraulic turbine having a runner, a draft tube of generally elbow formation turning the flow and discharging it substantially perpendicular to the runner axis, said draft tube including a horizontal partition curving from substantially vertical at its entrance end to substantially horizontal at its discharge end and having said entrance end located substantially in the centerline of the draft tube and having said discharge end located, substantially throughout its length, nearer to the upper and inner surface of the elbow than to the lower and outer surface.
17. In a rotary hydraulic machine having a runner, a velocity decelerating passage of generally elbow formation turning the flow after discharge from the runner and discharging the flow substantially perpendicular to the runner axis, said decelerating passage including a central pier lying in the central plane of the elbow, and a single partition perpendicular to said pier curving from a direction substantially parallel to the runner axis at its entrance end to a substantially perpendicular direction at its discharge end and having its discharge end substantially throughout its length, offset from the centerline of the passage toward the runner.
18. In a hydraulic turbine having a runner, a draft tube of generally elbow formation turning the flow and discharging it substantially perpendicular to the runner axis, said draft tube including a partition generated by straight lines perpendicular to the plane of the elbow and said partition curving from a substantially axial direction at its entrance end to a direction substantially perpendicular to the turbine axis at its discharge end and having said entrance end located substantially in the center line of the draft tube, the remainder of said partition deviating from the central line of the elbow passage by progressively increasing amounts from its entrance to its discharge end, said deviation being in a direction toward the center of curvature of the elbow.

LEWIS FERRY MOODY.
